DESIGN FOR A CAPE STOLE

Herman Hoch, New York, N. Y.

Application March 13, 1947, Serial No. 137,590

Term of patent 3½ years

(Cl. D3—3)

To all whom it may concern:

Be it known that I, Herman Hoch, a citizen of the United States of America, residing in New York city, county of New York, and State of New York, have invented a new, original, and ornamental Design for a Cape Stole, of which the following is a specification, reference being had to the accompanying drawing, forming part thereof, wherein

Figure 1 is a front elevational view of a cape stole, showing my new design.

Figure 2 is a rear elevational view of the cape stole shown in Figure 1.

I claim:

The ornamental design for a cape stole, substantially as shown.

HERMAN HOCH.
